Attorneys.

UNITED STATES PATENT OFFICE.

ALEXANDER McMUNN, OF PHILADELPHIA, PENNSYLVANIA.

WARPING-MILL APPARATUS.

1,387,858.

Specification of Letters Patent. Patented Aug. 16, 1921.

Application filed September 16, 1920. Serial No. 410,675.

To all whom it may concern:

Be it known that I, ALEXANDER McMUNN, a citizen of the United States, residing in the city of Philadelphia, county of Philadelphia, and State of Pennsylvania, have invented certain Improvements in Warping-Mill Apparatus, of which the following is a specification.

My invention is designed to provide improved means for spooling silk from warping reels and my principal objects are to provide mechanism which is adapted for use in conjunction with warping mills of various designs without changing such mills; to bring the operations within the ready control of the operator; and to simplify and strengthen the construction.

The characteristic features of my improvements will fully appear from the following description and accompanying drawings, in which Figure 1 is a side elevation of warping mill apparatus embodying my improvements; Fig. 2 is a top plan view of the same with parts removed and Fig. 3 is a front elevation of the driving mechanism.

As shown in the drawings, the warping mill frame 1 has journaled therein the arbors 2 of the reel 3 on which is fixed the driving band 4. A shaft 5, rotated by means of the pulley 6 and belt 7, has fixed thereto a wheel 8 frictionally engaging the band 4 to rotate the reel in the usual manner, the shaft 5 being preferably supported by a pivoted lever 5' operable by the treadle 5" to move the wheel 8 into and out of engagement with the band 4.

A pair of bifurcated standards 9, adapted to be secured to the floor in front of any type of machine, have journaled therein the spindles 10' and 10" of the roller 10 extending substantially across the front of the machine. A clutch disk 11 containing recesses 11' is pinned to the spindle 10' and is adapted for coaction with the complementary disk 12 journaled on the spindle 10" and provided with pins 12', the disk 12 containing a groove 13. A belt 14 disposed in the groove connects the disk 12 with the pulley 15 fixed on the shaft 5.

A bell-crank lever 16, pivoted on an arm 9' projecting from one standard, has at one end a yoke 17 in which are pivoted the pinches 18' of a collar 18, the latter being journaled in a channel 12" in the hub of the disk 12.

The bell-crank is normally elevated to keep the disks separated by a spring 19 fixed to the frame, but may be turned on its pivot to engage the disks by depressing the treadle 60 20 connected with the bell-crank by a link 21.

A spooling jack frame 22 has journaled therein a shaft 23 having fixed thereto between the frame members a pulley 24 engaged by a belt 25 passing over and adjustable along the roller 10. A wheel 26 fixed to the shaft 23 is provided with an internally toothed rim 26' meshing with the pinion 27 on the spool shaft 28. The shaft 28 is journaled in latched bearings 29 and 70 adapted to have fixed thereto a spool 30 on which the warp thread is wound from the reel 3.

By my improvements, a warping mill of any usual construction may be readily provided with automatic spooling means under complete control of the operator, the adjustment of the belt 25 on the roller 10 as the jack is moved across the mill providing a steady direct drive of the spool shaft. 80

When the warp on the reel 3 is to be taken off on the spool 30 the operator, having disengaged the wheel 8 from the band 4 by releasing the pressure on the treadle 5", attaches the end of the warp to the 85 spool 30 and depresses the treadle 20 whereby the bell-crank 16 is rocked to move the belt driven disk 12 into engagement with the clutch disk 11 pinned to the spindle 10' of the roller 10. The rotation of the roller 90 10 acts through the belt 25 to rotate the sheave 24 and therethrough and through the shaft 23, wheel 26, pinion 27 and shaft 28 rotates the spool 30 to wind the warp from the reel. 95

Having described my invention, I claim:—
1. In apparatus of the character described, the combination with a warping mill having a reel and means for rotating it, of a roller journaled in bearings independent of said mill, clutching mechanism through which said roller is connected with said reel rotating means, a spooling jack having a pulley, and a belt connecting said pulley and roller. 100

2. In apparatus of the character described, the combination with a warping mill having a reel and means for rotating it, of standards having a roller journaled therein, clutching mechanism connected with said roller, a belt connecting an element of said clutching mechanism and said reel ro- 110

tating means, a lever pivoted on a standard aforesaid for operating said clutching mechanism, and a spooling jack connected with and driven from said roller.

5. In apparatus of the character described, the combination with a warping mill having a reel and means for rotating it, of a pair of standards having a roller journaled therein, mechanism comprising a 10 clutch connecting said reel rotating means

and roller, a spooling jack frame having a shaft journaled therein, a sheave on said shaft between the frame members, a belt connecting said roller and sheave, a spool shaft, and epicyclic gear mechanism connecting said shafts. 15

Signed at Philadelphia, in the county of Philadelphia and State of Pennsylvania, this 11th day of Sept., 1920.

ALEX. McMUNN.
